Primary Examiner — Deanna L Pratt

(57) **CLAIM**

The ornamental design for a mounting bracket for television stand, as shown and described.

DESCRIPTION

1. Mounting bracket for television stand

1.1 : Perspective

1.2 : Perspective

1.3 : Front

1.4 : Back

1.5 : Left

1.6 : Right

1.7 : Top

1.8 : Bottom

1.9 : Reference

1.10 : Reference

The parts shown by means of broken lines in the reproductions are not part of the claimed design; the dotted-dashed lines show only the boundary between the claimed part and the other part; reproductions **1.9** and **1.10** are reference views and form no part of the claimed design; reproduction **1.9** is a reference view showing the state in use.

1 Claim, 10 Drawing Sheets
